UNITED STATES PATENT OFFICE

THEODORE A. SMITH, OF RIDGEWOOD, NEW JERSEY, ASSIGNOR TO RADIO CORPORATION OF AMERICA, A CORPORATION OF DELAWARE

TELEVISION SCANNING SYSTEM

Application filed April 1, 1929. Serial No. 351,514.

The present invention relates to television systems, and, particularly, to a method and means by which the television subject may be scanned or analyzed and then reproduced on a screen or the like.

It has heretofore been the custom in television systems of the type most common, such as in the rotating disk or mirror disk, or drum scanning and reproducing systems, to scan the field by means of a number of successive parallel lines formed from a series of points of light traced across the field. Such scanning action breaks the picture or subject to be transmitted or reproduced into a number of divisions, usually horizontal, although a vertical division is also of the same general type. With this type of system a spot of light is caused to move horizontally or vertically across the field or subject from one edge to the other, and then to move once more across the field or subject along a parallel line adjusted to but lower than or to the right or left from the previous line. This action is then repeated until the complete field or subject has been scanned or analyzed by a plurality of built-up horizontal or vertical lines. Such action is repeated at a rate of at least 16 times per second in order that the complete subject may be scanned at a rate corresponding to the persistency of vision of the human eye so as to produce the effect of an optical illusion in which the entire picture appears to be simultaneously projected upon the screen, although, in reality, successive points and lines are projected, but each point or line is repeated at a rate corresponding to the persistency of vision.

With a system of the above described type objection has been found in the fact that in the case of horizontal scanning any diagonal lines appearing in the subject are reproduced as stepped lines, and curved lines are reproduced at the receiver as a jagged line of the average curvature of the original line. Another objection resides in the fact that although the received picture may be transmitted and reproduced in its entirety by a rate greater than the repetition necessary to produce the optical illusion of a continuously moving picture, or, at a rate at least equal

to the persistency of vision, a pronounced flicker appears. This is apparently due to the fact that the picture has not been projected upon the screen in its entirety but was built up of successive elements, and, because of the fact that while the upper part of the picture is being scanned and reproduced, the human eye fails to retain the image of the lower portion of the picture and this latter portion, therefore, appears dark. This dark band at the opposite portion of the picture from that which is being scanned appears to travel up and down or across the screen, and thus causes an annoying flicker when a person views the received image.

Therefore, as a principal object of this invention, I have sought to develop a method and means for substantially eliminating the undesirable flicker from received television images.

As a further object of my invention, I have sought to develop a method and means by which a television subject may be scanned or analyzed, and then reproduced in a sequential manner along paths bearing an angular relationship to each other so as to reduce flicker to a substantial degree.

Still a further object of my invention is to provide a method and means by which a television subject may be scanned and then reproduced so that diagonal or curved lines in the original subject may be free from any substantial distortion and will not appear as stepped lines.

Still other objects of my invention are to produce a method and means for scanning and reproducing television subjects which is simple in its construction and arrangement of parts, a system which is easily operated, readily installed, conveniently set up, substantially fool proof in its operation, and efficient in its use.

Still other and ancillary objects of my invention will at once become apparent and suggest themselves to those skilled in the art to which the invention has been directed by a reading of the following specification in connection with the accompanying drawings, wherein, the various figures diagrammatically and conventionally represent a

system for either scanning or reproducing a television subject according to my novel method of scanning and reproducing along different paths in a sequential manner.

5 By the accompanying drawings, Fig. 1 represents a suitable means for scanning in a vertical direction, and Fig. 2 represents a suitable means for scanning in an angular direction to that shown by Fig. 1, or along lines in a horizontal direction.

10 Fig. 3 shows the system of Figs. 1 and 2 combined into a single figure, wherein for the position shown the light from the source will be caused to trace a vertical path upon the 15 picture screen, while for the horizontal path which will be traced upon further rotation of the scanning element, the assumed path is shown by dotted lines. Fig. 4 graphically represents the relationship between the series 20 of lines produced by each of the fixed reflecting systems cooperating with the rotatable scanning element.

More particularly, my invention has been directed to a system in which the scanning action takes place in a sequential manner by alternating between horizontal and vertical lines of scanning so that the successive lines by which the picture is analyzed will be at right angles to each other, although 30 it is to be recognized that where desired, and without departing from the basic principles of my invention, the angle which successive scanning actions bear to each other may vary within wide degrees, and may be 35 at any angle suitably chosen.

Thus, to describe, for purpose of illustration, the system as one in which the picture is first analyzed along horizontal lines, then along vertical lines, and then analyzed again 10 and again by repeating this process, the human eye is unable to distinguish the particular direction of reproducing each of the 15 separate pictures on account of their rapidity, and the resultant picture appears as a combination of the two distinct types of scanning motion. The produced picture may appear to be broken up into small squares instead of lines, but the division between 20 squares will be much dimmer than those between the lines, and therefore less objectionable; and further, the stepped effect is substantially reduced because of the fact that it is entirely different for the two types of scanning, and the combination of the two 25 types of scanning neutralizes the distortions in each direction and the combined picture appears more natural than that produced along either of the component lines of scanning. Further than this, it is possible to 30 reduce the flicker to a material extent because of the changing in direction of the moving band and because of the fact that the flicker frequency would be substantially changed.

65 To refer now more particularly to the ac-

companying drawings forming a part of this invention, I have illustrated, by way of example, a disk member 1 provided about its periphery with two complete and distinct sets of mirrors generally designated 3 and 5, in which the mirrors of the set 3 are so tilted and stepped as to the angle of tilting that they reflect light beams consecutively along different parallel paths but at an upward direction from the drum, and the 70 mirrors forming the portion 5 of the drum are so tilted and stepped that they reflect light beams downwardly from the disk or drum along adjacent parallel paths.

The drum disk 1 may be mounted in any 75 convenient manner upon a spindle 7, for example, and rotated from any desired type of prime mover (not shown), for example, a synchronous motor whose rotation is controlled by incoming television signals of the 80 general type described and claimed in my copending application, Serial #322,704, filed November 30, 1928, and driven in the direction indicated by the arrow appearing on the 85 drum disk.

90 As shown, the arrangement has been particularly directed to a television reproducing system, wherein, incoming television signals are arranged to illuminate the glow lamp 9 so as to produce a glow therein. The 95 light from the lamp 9 is then directed by means of a lens system 11 so as to project itself as a point source on the drum disk 1 at a point 13, for example, as shown. It is preferable, although not essential, to provide 100 a glow lamp in which the illumination therefrom is as a point source so that it may be more readily focused as a point source upon the individual mirrors forming the series 105 3 or 5 of the drum disk 1. As the drum disk 1 is rotated in the direction shown by the arrow, the point of light focused thereon by means of the lens system 11 is caused to travel across the mirror, and thus, due to the 110 change in angular position of each adjacent mirror, the light beam from the glow lamp or other appropriate source is reflected along different paths.

115 As shown particularly in connection with Fig. 1 of the drawings, the light beams issuing from the glow lamp source 9 have been shown as directed against the set of mirrors 3 so as to be reflected in an upward direction from the disk 1 so as to travel along a path 15, for example, where they will impinge upon a stationary mirror 17 and trace paths thereacross in a direction indicated by the arrow. From the mirrors 17, the light is again reflected along a path generally designated as 19, and is projected upon a second stationary mirror 21 from which it is reflected along a path 23, for example, so as to trace lines in a vertical direction thereacross shown by the arrow, so that over half of a revolution 120 125

of the disk 1, a complete picture of the television subject is built up upon the screen 25 in a vertical manner, so that consecutive lines of reproduction are parallel to each other 5 and extend across the screen 25 in the direction shown by the single line 27 indicating the manner in which the picture is built up.

Now referring more particularly to Fig. 2, after the disk or drum 1 has turned through 10 a half revolution so as to bring the light beams issuing from the glow lamp 9 upon the set of mirrors 5, the light beams are reflected from the mirror surface of the disk 1 along a path generally designated as 29 to a 15 stationary mirror 31 arranged below the drum disk 1. The stationary mirror 31 is tilted at an appropriate angle so that light beams reflected therefrom along a path 33, for example, will trace horizontal paths 35 20 across the screen 25 in the direction as shown by the arrow.

It is thus seen that the stationary mirrors 17, 21 and 31 must be fixed and appropriately located so that the angle of tilting thereof 25 is such that all light reflected from the mirror surfaces composing groups of mirrors 3 and 5 upon the drum 1 will eventually be projected as a point source upon the screen 25. Thus, as the drum 1 is rotated, the lines 30 by which the picture is reproduced will sequentially or alternately and successively be composed of groups of horizontally extending lines due to the reflection of the group of mirrors 5, and vertically extending parallel 35 lines due to the reflection of the group of mirrors 3 upon the drum disk 1.

After the picture is horizontally scanned or reproduced the vertical scanning and reproduction is repeated.

40 As has been shown, the drum disk 1 is composed of two distinct sets of mirrors, 3 and 5, and each of these sets of mirrors may preferably be of such a number that the complete picture will be reproduced therefrom, and 45 supposing, for example, that a fifty line picture were to be desired, the drum 1 should carry about its periphery one hundred distinct mirror surfaces. This number of mirrors would be divided into two groups, 3 and 50 5, wherein, the fifty mirrors of group 3 should all be arranged to reflect light in an upward direction, for example, from the disk, and the fifty mirrors of group 5 should be arranged to reflect light in a downward 55 direction from the drum. It is thus apparent that by utilizing a scheme of the type herein described, it is possible also to reduce the speed of rotation of the disk member by fifty percent, although due to the increase in the 60 number of mirrors about the periphery of the disk, the peripheral speed of the disk must be increased over that of a disk having a smaller number of mirrors.

According to the above description, the 65 system has been described separately as to

the vertical and horizontal scanning as produced respectively by the arrangements of Figs. 1 and 2, but it should be understood that both of the arrangements of Figs. 1 and 2 are operating in a sequential manner, and the system as a whole has further been schematically shown by Fig. 3, wherein the controlled light source is in the position of the disk shown adapted to produce a vertical line upon the screen, whereas, upon further rotation of the disk, so that the light from the source 9 reaches the mirror surface 5, horizontal lines will be produced upon the screen, as shown by the dotted line paths 29 and 33, which are respectively directed and reflected to and from the stationary mirror surface 31.

The vertical and horizontal paths of reproduction are conventionally illustrated by Fig. 4, wherein the lines 27, 27 show the vertical scanning paths, while the lines 35, 35 show the horizontal scanning paths which occur after the picture has been rebuilt completely along vertical paths, and then continue until the picture has been reproduced completely along horizontal paths, at which time the vertical scanning is repeated.

It will also be apparent that a scheme of the type herein described may also be readily applied to a lens disk or drum without materially changing the construction and arrangement of parts, and I, therefore, desire to make all such modifications and changes as may readily suggest themselves to those skilled in the art to which the invention relates, provided, of course, such modifications and changes fall fairly within the spirit and scope of the invention as defined in the hereinafter appended claims.

Having now described my invention, what I claim and desire to secure by Letters Patent is the following:

1. In a television system, a mirror disk and associated reflector system cooperating with one portion of the said mirror disk for scanning and reproducing a television subject along a parallel set of lines extending in one direction across the subject, a second reflector system cooperating with the second portion of said mirror disk for scanning and reproducing the same subject along a second set of parallel lines extending at an angular direction to said first named set of scanning and reproducing lines, and means operable upon each half revolution of said disk for cyclically changing from one to the other of said sets of scanning and reproducing lines at a rate commensurate with the persistency of vision.

2. In a television system, a screen for reproducing a television subject, a rotary scanning element and a reflector system cooperating with a portion thereof for illuminating said screen along series of parallel paths extending transverse thereto, a second reflector system cooperating with the second portion of said rotary scanning element for illumin-

nating said screen at a later period of time along a set of parallel lines extending longitudinally thereof, and means dependent upon the rate of revolution of said rotary scanning element for alternately and successively changing from one to the other of said paths of illumination at a rate equal to that necessary to effectively maintain the impression that all of said lines are being continuously illuminated.

3. In a television system, a scanning and reproducing disk, a plurality of sets of fixed reflecting bodies associated with said disk, a light source for projecting light upon said disk, and means provided by said disk for tracing on said reflecting bodies a plurality of parallel paths of an intensity corresponding to the intensity of light and shadow on a picture subject, and means provided by said disk for cyclically shifting the said parallelly projected lines of illumination from one to the other of said reflecting bodies at periods when light values corresponding to the entire television subject have been projected upon each of said mirrors.

4. In a television system, a scanning and reproducing disk, a plurality of sets of oppositely tilted mirrors about the periphery thereof, said mirrors being arranged in sets for alternately and successively projecting light impinging thereon in an upward and downward direction from the plane of said disk, whereby light impinging upon said disk may be caused to trace a pair of paths each composed of a group of parallelly extending lines extending at an angular direction with respect to each other.

5. In a television system, a scanning and reproducing disk, a plurality of sets of mirrors arranged about the periphery of said disk, one of said sets of mirrors being arranged to deflect light impinging thereon along a set of parallel lines upwardly from the plane of said disk, and the other of said sets of mirrors being arranged to project light downwardly from the plane of said disk along a set of parallelly extending lines, a mirror surface positioned above said disk along the path of reflected light beams therefrom, a screen, means associated with said mirror for tracing paths of illumination upon said screen in a direction extending vertical thereof, a mirror arranged beneath said disk for tracing paths of illumination upon said screen in a horizontal direction, and means for rotating said disk and changing from one to another of said paths at a rate commensurate with the persistency of vision.

6. A television system for scanning and reproducing television subjects including a light source, a rotating disk arranged in the path of said light, a plurality of sets of mirrors arranged about the periphery of said disk, one of said sets of mirrors being arranged to continuously project the light im-

pinging upon the periphery thereof along a set of parallel lines in a plane above said disk, and the other of said sets of mirrors arranged to project the light impinging thereon along a set of parallel lines in a plane beneath said disk, a screen for reproducing a television image, a mirror positioned beneath said disk for reflecting the light projected thereon from said disk as a plurality of sets of parallel lines and tracing the same across said screen as a set of parallel lines horizontally thereof, a mirror positioned above said disk for reflecting the light beams projected as parallel paths of light upwardly from said disk, and a second diagonally positioned mirror associated with said last named mirror for tracing the light beams projected upwardly from said disk as a set of parallelly extending lines vertically upon said screen, and means provided by the rotation of said disk for cyclically changing from one to the other of said sets of parallel lines of reproduction at a rate commensurate with the persistency of vision.

7. In a television system, a screen for reproducing a television image, a scanning and reproducing disk, a light source for projecting light upon said disk, a plurality of sets of mirrors arranged about the periphery of said disk, one of said sets of mirrors being arranged to deflect light impinging thereon along a set of parallel lines upwardly from the plane of said disk, and the other of said sets of mirrors being arranged to project light downwardly from the plane of said disk along a set of parallelly extending lines, a mirror surface positioned above said disk along the path of reflected light beams therefrom, means associated with said mirror for tracing parallel paths of light upon said screen in a direction extending vertical thereof, a mirror arranged beneath said disk for tracing parallel paths of light upon said screen in a horizontal direction, and means for rotating said disk and changing from one to another of said paths at a rate commensurate with the persistency of vision.

8. A system for scanning and reproducing television subjects including a source of illumination, a rotating disk arranged in the path of said illumination, a plurality of sets of mirrors arranged about the periphery of said disk, one of said sets of mirrors being arranged to continuously project the light impinging thereupon along a set of parallel lines upwardly from said disk, and the other of said sets of mirrors arranged to project the light impinging thereon along a set of parallel lines downwardly from said disk, a screen for reproducing a television image, means positioned beneath said disk for reflecting the light projected in one direction from said disk and cause said light to focus on said screen to trace a set of parallelly extending lines horizontally of said screen,

- means positioned above said disk for reflecting the light beams projected in a second direction from said disk and cause said light to focus on said screen to trace a set of parallelly extending lines vertically upon said screen, and means provided by the rotation of said disk for cyclically changing from one to the other of said sets of parallel lines at a rate commensurate with the peristancy of vision.
- 5 9. In a television system, a rotary scanning and reproducing element and a plurality of sets of reflecting systems cooperating therewith for causing different portions of said rotary scanning element to trace light paths 10 bearing an angular relationship to each other.
10. In a television system, a scanning and reproducing element having a set of upwardly tilted mirrors and a set of downwardly tilted mirrors about the periphery thereof 20 for projecting light impinging thereon in an upward and downward direction from the plane of said disk, and a plurality of fixed reflecting systems cooperating therewith 25 whereby light impinging upon said disk may be caused to trace alternately a pair of paths each composed of a group of parallelly extending lines each extending at an angular direction with respect to each other.
